UNITED STATES PATENT OFFICE.

HERBERT T. HERR, OF PITTSBURGH, PENNSYLVANIA, ASSIGNOR TO WESTINGHOUSE ELECTRIC & MANUFACTURING COMPANY, A CORPORATION OF PENNSYLVANIA.

STOKER CONTROL.

1,375,250.

Specification of Letters Patent. Patented Apr. 19, 1921.

Application filed November 6, 1915. Serial No. 60,073.

To all whom it may concern:

Be it known that I, HERBERT T. HERR, a citizen of the United States, and a resident of Pittsburgh, in the county of Allegheny and State of Pennsylvania, have made a new and useful Invention in Stoker Control, of which the following is a specification.

This invention relates to automatic control mechanism and has for a special object 10 to produce a control mechanism which will automatically control the operation of a mechanical stoker by varying the fuel and the air supply to the stoker in accordance with variations in the pressure of the steam generated by a steam generator or boiler 15 operating in conjunction with the mechanical stoker.

A further and more general object of the invention is to produce a new and improved 20 control mechanism capable of independently controlling a number of separate mechanisms or devices in response to variations in the result accomplished by the coöperation of all the devices.

25 A still further object of the invention is to produce a new and improved control mechanism, which is responsive in operation to variations in the pressure of the steam supplied by a steam generator, and 30 which controls the operation of a mechanical stoker operating in conjunction with the steam generator.

These and other objects, which will be 35 made apparent throughout the further description of the invention, are accomplished by means of apparatus embodying the features herein described and illustrated in the drawings accompanying and forming a part hereof.

40 In the drawings: Figure 1 is a more or less diagrammatic view of apparatus embodying my invention, portions being shown in section for convenience of illustration.

Fig. 2 is a vertical sectional view of a 45 control mechanism for a blower or fan, which mechanism forms a detail of the apparatus illustrated and a part of my present invention.

Fig. 3 is a sectional view of a pressure responsive device forming a detail of the present invention, and which is illustrated on a reduced scale in Fig. 1.

Fig. 4 is a sectional view of a pressure responsive device, which may be substituted 55 for the device illustrated in Fig. 3.

Fig. 5 is a vertical sectional view of a relay mechanism which forms a part of the present invention and which may be substituted for the relay mechanism shown in Fig. 1.

Fig. 6 is a sectional view taken at right angles to the view illustrated in Fig. 5, and illustrates a portion of the mechanism there illustrated.

Fig. 7 is a sectional view of a governor 65 which forms a detail of the present invention.

Fig. 8 is a detailed sectional view of the 70 control valve of the relay mechanism illustrated in Fig. 1.

The apparatus illustrated as an embodiment of my invention is adapted to control the operation of one or more mechanical stokers in response to variations in the pressure of the steam delivered by one or more 75 steam generators or boilers operating in conjunction with the stoker or stokers. It includes a pressure responsive device which is responsive in operation to the pressure of the steam delivered by the generator or generators, or to the pressure of the steam in a steam supply pipe and operates through the agency of a relay mechanism to increase the actuating pressure delivered to one or more control mechanisms as the steam pressure 80 falls off and vice versa, to decrease the actuating pressure delivered to the control mechanisms as the steam pressure increases.

As illustrated, the control mechanisms are 85 adapted to control the operation of fans or blowers delivering forced draft to one or more furnaces and the operation of an engine or motor which drives the fuel delivery mechanisms of the mechanical stokers with which the furnaces are equipped. It will, 90 of course, be understood that one or more of the control mechanisms may be employed to actuate dampers, etc., and that consequently the air supply to the furnace or furnaces may be controlled in installations 100 employing natural draft as well as in installations employing forced draft.

Referring to Fig. 1, the apparatus includes a pressure responsive device 10, which communicates with a steam supply 105 pipe 11, and is adapted to control the delivery of fluid under pressure to a relay operating mechanism 12. As illustrated, fluid under pressure is delivered by the device 10 to the mechanism 12 from a com- 110

pressor 18, which is preferably adapted to supply air under a constant and determined pressure. While I have illustrated the apparatus as including an air compressor, it 5 will be understood that any fluid under pressure may be employed and that I employ the term fluid in its broad sense to include liquids as well as gases. The mechanism 12 controls the operation of a relay mechanism 10 14, which delivers air under pressure to the control mechanisms 15 and 16 through a pipe 17, and which is adapted to vary the pressure of the air so delivered in response to variations in the pressure of the steam 15 supplied to the device 10.

The control mechanisms 15 are each adapted to control the operation of an engine or turbine 15^a driving a fan or blower 15^b which delivers air to the furnace or 20 furnaces 15^c operating in conjunction with the steam generator or generators 15^d supplying steam to the steam pipe 11, and one of these mechanisms is illustrated in Fig. 2. The control mechanism 16 consists of a 25 pressure controlled governor, illustrated in detail in Fig. 7, and adapted to control the operation of a stoker engine 19, which drives the mechanical stoker or stokers 19^a operating in conjunction with the steam generator 30 or generators supplying steam to the pipe 11. As illustrated, the engine 19 drives the stoker or stokers 19^a by means of a lay shaft 19^b in a manner well known to those skilled in the art.

35 As illustrated in Figs. 1 and 3, the device 10 includes a casing provided at one end with a steam chamber 20, which communicates with the pipe 11 by means of a pipe 21. It will, of course, be understood that 40 the illustration in Fig. 1 is diagrammatic and that the pipe 21 would, in large stoker installations, communicate directly with the steam header receiving steam from all of the generators included in the unit to be controlled. The steam chamber 20 is located 45 between one end of the casing and a flexible wall or diaphragm 22 against the outer face of which a plunger 23 is held by means of a coiled spring 24. As illustrated, the 50 spring operates between the plunger and an adjustable spring seat 25, which is screwed into the casing and is capable of being turned to different positions for the purpose of varying the tension of the spring. The 55 plunger is provided with a stem 26, which abuts against a flexible wall or diaphragm 27 forming one wall of fluid delivery chamber 28. The plunger 23 and its stem 26 are so proportioned that a movement of either 60 of the diaphragms toward the plunger will laterally displace the other diaphragm. A spring seated valve 29 is located within the casing and controls the delivery of fluid, hereinafter termed air, from a pipe 30 to 65 the chamber 28. This valve is so construct-

ed that it co-operates with the diaphragm 27 in controlling communication between the chamber 28 and the atmosphere. In the illustration this is accomplished by providing the valve with a hollow stem 31, which 70 forms a means of communication between the chamber 28 and the atmosphere and is adapted to be engaged by the diaphragm 27 both for the purpose of closing communication between the chamber and the atmosphere 75 and of lifting the valve from its seat and establishing communication between the chamber and the pipe 30. The chamber 28 is provided with a delivery port, which communicates through pipe 32 with the relay 80 operating mechanism 12 and is therefore adapted to either deliver air under pressure to the mechanism 12 or to exhaust the mechanism by establishing communication between it and the atmosphere. 85

As illustrated, the mechanism 12 includes a casing 33, which incloses a plunger 34 and with the lower end of which and below the plunger, the pipe 32 communicates. The plunger is provided with a stem 35, 90 equipped at its outer end with a rack 36. A coiled spring 37 surrounds the stem 35 and operates between one end of the casing 33 and the plunger 34 to oppose movements of the plunger in response to air pressure 95 delivered through the pipe 32. Movements of the plunger, in response either to air or spring pressure, actuate a cam 38 through the agency of a gear 39 mounted on a cam shaft 41 and meshing with the rack 36. The 100 cam shaft 41 is diagrammatically shown in perspective for the purpose of simplifying the illustration, and as illustrated in Fig. 1, the mechanism 12 is supposed to be located behind and to one side of the relay mechanism 14. The relay mechanism is clearly described and illustrated in my Patent No. 1,209,579, granted December 19, 1916, and entitled "Fluid distributor," which was filed by me on May 1, 1913; consequently a brief 110 description only will be given.

The cam 38 forms a part of the relay mechanism and is adapted to control the operation of a tubular or hollow rod 39^a which in effect forms an air delivery valve 115 controlling the delivery of air to and the discharge of air from a central pressure chamber 30^a of that mechanism.

The mechanism 14 also includes two end chambers, 11' and 12'; the former of which 120 is inclosed between an end wall of the mechanism casing and a diaphragm 13^a, and the latter of which is inclosed between the other end wall of the casing and a diaphragm 14^a. The diaphragm 13^a controls the operation 125 of a discharge valve 24^a adapted to place the chamber 11' in direct communication with the atmosphere; and the diaphragm 14^a controls the operation of a valve 16^a, which is adapted to control the delivery of 130

air under pressure from a passage 69^a to the chamber 12' and consequently to the chamber 11', since these chambers communicate with each other through the passage P which is clearly shown at 56 in Patent No. 1,209,579. The passage 69^a receives air under pressure from the compressor 13 through the pipe 30 and a branch pipe 56. A branch passage 29^a delivers air under pressure to the hollow rod 39^a having one end closed by a plug 40 adapted to bear against the cam 38. The hollow rod 39^a is provided with openings 41 always registering with the inlet passage 29^a so that air may pass from the passage 29^a into the rod. The hollow rod 39^a is normally closed at the end farthest from the point 40 by a piston valve 42 which slides in a piston 43 which is provided with openings 44 adapted to register with openings 45 in the tube. The valve 42 for the hollow rod 39^a is adapted to cover a central port 46 in the piston through which air may exhaust and pass out through the ports 47 and 48 to the atmosphere. The valve 42 is provided with a pin or projection 49 around which is a coil spring 50, one end of which bears against the valve 42 and the other against a spring seat 51 in the piston 43. One end of the piston 43 is provided with a point bearing 52 which seats against a spring-pressed seat 53. One end of a coil spring 54 abuts against seat 53 and the other end bears against a screw plug 55, being adapted to be used as an adjustment for varying the tension of the spring 54.

The arrangement is such that as the cam 38 is turned, in response to the decreasing air pressure within the mechanism 12, it forces the tubular valve 39^a inwardly, thereby uncovering the ports 45 and delivering air under pressure to the central chamber 30^a. As this pressure builds up, the plunger 43', moving in response to it and in opposition to the spring 54, closes the ports 45, thereby establishing a determined pressure within the chamber 30^a for each position of the cam 38 and consequently of the valve 39^a. As is described in said prior patent, the plunger also operates to discharge air from the chamber 30^a through a port 48, when the pressure exceeds that for which the valve 39^a is set. The pressure in the chamber 30^a operating upon the diaphragms 13^a and 14^a presses the valve 24^a against its seat and opens the valve 16^a, thereby admitting high pressure air to the chambers 12' and 11'. The pressures in these chambers will therefore build up until equilibrium is established between them and the chamber 30^a, at which time the valve 16^a will close. A further building up of the pressures within the chambers 11' and 12' will cause the diaphragm 13^a to open the valve 24^a and discharge excess pressure to the atmosphere.

In this way the relay mechanism 14 adjusts the pressure delivered to the control mechanisms in accordance with variations in steam pressures; it may be so adjusted that the air pressure delivered by it will vary in any desired ratio with relation to variations in the steam pressure encountered by the device 10.

It will, of course, be apparent that a receiver and a constant pressure valve may be located between the compressor 13 and the piping 30, which delivers air under pressure to the device 10 and the mechanism 14.

One of the control devices 15 is illustrated in Fig. 2 on an enlarged scale and is adapted to control the steam delivery valve of an engine or turbine 15^a driving one of the fans or blowers supplying forced draft to one of the furnaces included in the unit controlled. As illustrated, the mechanism 15 includes a plunger 57, which is exposed on one side to the air pressure, delivered by the relay mechanism 14, through a branch pipe 58, and which is operatively connected to a diaphragm 59 located within a pressure chamber formed within the casing of the mechanism. The diaphragm 59 divides the pressure chamber into a compartment 60, open to the atmosphere through a port 61, and a compartment 62, which communicates with the delivery port of the blower controlled, through a pipe or passage 63, and is consequently exposed to the air pressure delivered by the blower. The stem of the plunger 57 projects through the diaphragm 59 and is provided with an extension 64, on which the throttle valve 65 of the engine, driving the controlled blower, is mounted. As illustrated, the valve 65 is a balanced valve and controls communication between a steam inlet pipe 67 and a steam delivery pipe 66, which communicates with the blower driving engine. The air pressure delivered by the mechanism 14 operating on the plunger 57 tends to further open the valve 65 and to thereby deliver additional steam to the driving engine. This pressure on the plunger is however opposed by the pressure delivered by the controlled blower and operating on the diaphragm 59 and consequently the diaphragm will tend to close the valve as the output of the blower is increased. In this way the valve 65 will control the operation of the blower in response to the air pressure delivered through the branch pipe 58, and the output of the blower will vary in response to variations in the pressure of the steam delivered to the device 10.

In the drawings I have shown a coiled spring 68 arranged to supplement the air pressure delivered to the plunger 57. This spring is capable of being adjusted by means of thumb screw 69 and consequently imposes an initial pressure on the plunger which is 130

independent of the air pressure delivered through branch pipe 58. In this way the valve 65 is maintained open and the blower is kept in operation even though the steam pressure delivered to the device 10 is such that no air under pressure is delivered to the control mechanism by the relay mechanism 14. This spring may, of course, be so adjusted that the supply of steam delivered to the engine or turbine driving the blower will be just sufficient to keep the blower in operation, and, as above described, the diaphragm 59 will operate to close the valve in case the air pressure delivered by the blower exceeds the pressure for which the spring 68 is adjusted.

The control mechanism 16 is illustrated in section in Fig. 7 and comprises a governor for the stoker engine 19 or the engine which operates the fuel feeding mechanism of the various mechanical stokers included in the controlled apparatus. This governor is adapted to control the admission valve of the engine 19 in the ordinary manner, except that it is provided with an air actuated plunger for counteracting or opposing the centrifugal force exerted by the governor balls.

The admission valve (not shown) of the stoker engine 19 is actuated by means of a lever 70, provided with a control spring 71 which, as illustrated, normally tends to open the valve and to hold the free end of the lever against a governor spindle 72. A pressure actuated plunger 73 is mounted on the spindle 72 and operates within a cylinder 74. A spring 75 is located within the cylinder 74 so as to oppose the motion of the piston in response to fluid pressure and so as to oppose the valve opening pull of the spring 71 on the lever 70. This spring is preferably so proportioned that it will prevent the governor from hunting by imposing a pressure on it which will gradually increase as the governor balls move outwardly. The governor balls 76 are mounted on links in the usual manner and are adapted to oppose the pressure of the air acting on the plunger 73 and to close the valve of the engine 19 as the engine's speed increases. As is illustrated, the cylinder 74 is mounted on a driven shaft of the engine and one set of the governor ball links are pivoted on it. The other set of links are pivoted on pins which are carried by the plunger 73 and project through slotted openings in the cylinder. Air under pressure is delivered to the cylinder 74 through the hollow interior of the governor spindle 72, which is provided with a telescoping delivery pipe 77 connected to and receiving air under pressure from a branch pipe 78 which communicates with the air delivery pipe 17. With this arrangement the spring 75 normally presses the governor spindle 72 against the thrust bearing 79,

with which the free end of the lever 70 is provided, and air under pressure, entering the cylinder, varies the effectiveness of the governor by exerting pressure on the plunger 73, which tends to move it in opposition to the pressure of the spring 75 so that the spring 71 is free to move the lever 70 to open the engine admission valve. Variations in the pressure delivered to the cylinder 74 by the mechanism 14 will therefore vary the adjustment of the governor and consequently vary the speed of the engine 19.

The operation of the apparatus is as follows: As the steam pressure in the pipe 11 decreases below the desired or determined pressure or that for which the spring 24 of the device 10 is adjusted, the diaphragm 22, moving in response to the pressure of the plunger 23, permits the diaphragm 27 to move in response to the pressure of the air in the chamber 28 and away from the inner end of the valve stem 31 of the valve 29. This insures the closing of the valve 29 and places the delivery chamber 28 in communication with the atmosphere through the hollow stem 31. The chamber 28 and consequently relay control device 12 are thereby exhausted and consequently the plunger 34 moves, in response to the pressure of the spring 37, and shifts the position of the cam 38 so as to introduce air under pressure to the central chamber 30^a of the mechanism 14. As has been described, the degree of pressure admitted to the chamber 30^a is determined by the position of the tubular valve 39^a and consequently by the position of the actuating plunger 34. The admission of pressure within the central chamber 30^a causes a corresponding pressure to be delivered to the chambers 11' and 12' of the mechanism 14 and consequently to each of the controlling mechanisms 15 and 16. It has already been described that an increase in the pressure delivered to the plungers 57 of the mechanisms 15 will open the steam delivery valves of the engine driving the blowers and increase the output of the blowers. It has also been described that an increase in the pressure delivered to the piston 73, of the control mechanism 16, will cause the engine 19 to speed up by increasing the limits between which the engine governor operates.

As the steam pressure builds up in response to the operation of the organized control mechanism the diaphragm 22 of the device 10 moves first to close the inner end of the valve stem 31 by forcing the diaphragm 27 against it and then, continuing its movement, opens the valve 29. The opening of the valve 29 admits air under pressure to the chamber 28 and consequently to the plunger 34 of the relay control mechanism 12. The delivery of air under pressure to the chamber 28, however, augments the pressure of the spring 24 and tends to move the plunger 130

23 downwardly or in opposition to the steam pressure exerted on the diaphragm 22. Consequently, when the pressure within the chamber 28 and the pressure of the spring 24 and the spring controlling valve 29 preponderate over the steam pressure exerted on diaphragm 22, the plunger 23 will move downwardly and the valve 29 will close. This preponderance in pressure, however, 10 cannot continue, since the diaphragm 27 will move away from the inner end of the stem 31 and, establishing communication between the chamber 28 and the atmosphere, reduce the pressure within the chamber 28. 15 With such an arrangement of apparatus, the pressure delivered to the chamber 28, and consequently to the relay control device 12, will be automatically adjusted until equilibrium is established, and the plunger 34 20 will therefore occupy definite and determined positions for different steam pressures delivered to the diaphragm 22 of the device 10. The cam 38 will, therefore, occupy definite positions for different steam 25 pressures encountered and consequently the relay mechanisms will proportion the pressure of the air delivered by it in response to variations in the pressure of the steam within the pipe 11 or the steam pipe communicating with the device 10. 30

In Fig. 1, I have shown a hand lever 81, which is mounted on the cam shaft 41 and which may be employed in turning the cam to any desired position and locking it in 35 this position so as to relieve the mechanism 14 of the automatic control of the device 12. With this arrangement, the mechanism 14 may be set to deliver any desired pressure, within possible limits, to the various control mechanisms, and this pressure will be maintained independently of variations in 40 the steam pressure delivered by the steam generator or generators controlled.

In Figs. 5 and 6, I have illustrated a 45 modified form of apparatus, which may be employed for controlling the air pressure delivered to the control mechanisms 15 and 16. This mechanism may replace the devices 10 and 12 and the relay mechanism 50 14 of Fig. 1.

It includes a chamber 82, adapted to receive steam, through a passage 83, from a steam header or pipe communicating with the boiler or boilers to be controlled. The 55 chamber is provided with a flexible wall or diaphragm 84, against the outer face of which a plunger 85 is pressed by means of an adjustable spring 86. A pilot piston 87 is located within a cylinder 88, with 60 which the mechanism is provided, and is operatively connected to the plunger 85, by means of a piston rod 89, so that it moves with the plunger. The cylinder 88 is provided at one end with an exhaust port 91, 65 and near its middle portion with a fluid de-

livery port 92, which communicates, by means of passages 93, with the pressure chamber 94 of a relay mechanism 95. The cylinder is also provided with one or more inlet ports 96 which communicate with a 70 source of compressed air through a passage 97 and a branch passage 97', and which are controlled by the piston 87. As illustrated, the piston 87 is hollow and is provided with radial passages 98, adapted to coöperate with the port or ports 96 in admitting pressure to the cylinder. In the illustration, the upper end of the pilot piston is provided with a passage 99, in open communication with its hollow interior and with the upper 75 end of the cylinder 88, while the lower end of the piston is provided with a valved passage adapted to establish communication between the upper end of the cylinder and the exhaust port 91. The valve shown in 80 this passage is a ball valve 100 and is adapted to be unseated by an adjustable stationary pin 101, when the piston 87 moves downwardly past a determined position.

A drop of steam pressure in the line, communicating with the passage 83, will permit the plunger 85 to move upwardly in response to the pressure of the spring 86. This will move the pilot piston 87 upwardly and cause its radially extending passages 95 98 to uncover the port or ports 96, thereby admitting air under pressure through the piston to the upper end of the cylinder 88. As the air pressure builds up within the cylinder it will exert an increasing downward pressure on the piston 87 and will finally augment the steam pressure, delivered to the chamber 82, to such an extent that the diaphragm 84, and consequently the plunger 85, will move to their normal position 100 in opposition to the spring pressure 86. As soon as this occurs the piston 87, moving with the plunger, will cut off communication between the passage 97' and the interior of the cylinder 88 by closing the port 110 or ports 96, consequently the counter-balancing air pressure delivered to the cylinder 88 will be retained within the cylinder. As before described, this pressure is transmitted to the chamber 94 of the relay device 115 95, through the passage 93, which is in open communication with the upper end of the cylinder 88.

It will be apparent that the degree of pressure delivered to the chamber 94, in 120 response to a given variation in the pressure of the steam within the delivery passage 83 or chamber 82, will be determined by the relative effective areas of the piston 87 and the diaphragm 84. For example, by 125 so constructing the piston 87 that its effective area is one-fourth the effective area of the diaphragm 84, a drop of one pound in the steam pressure in the chamber 82 will occasion a four pound increase of the air 130

pressure within the cylinder 88 above the pilot piston 87. In this way, the plunger 85 and its accessories operate as a pressure multiplying device.

5 An increasing pressure within the chamber 94 deflects a diaphragm 102, which separates the chamber 94 from a chamber 103, formed within the casing of the mechanism 95. This chamber 103 communicates, 10 by means of a passage 104, with a vent chamber 105 and also by means of a port 106, with the mechanisms 15 and 16 to be controlled. The mechanism 95 is also provided with a pressure chamber 107, which 15 communicates, by means of a passage 108, with the source of supply of air under pressure through the pressure delivery passage 97. A spring closed valve 110 is located between the chamber 107 and the chamber 20 103, and is provided with an inwardly projecting stem 111, which is adapted to be engaged by a finger 112, mounted on the diaphragm 102, and to thereby establish communication between the chambers 107 25 and 103 by opening the valve, when the diaphragm 102 deflects in response to a preponderating pressure within the chamber 94. The chamber 105 is provided with a relief 30 valve 113, which is spring closed and which is adapted to control the communication between that chamber and a vent port which communicates with the atmosphere. This valve like the valve 110 is provided with an inwardly projecting stem 114, which is located on the opposite side of the diaphragm 102 from the valve 110, but is adapted to be engaged by the stem 114 when the diaphragm deflects in response to a preponderating 35 pressure within the chamber 103.

40 With this arrangement the pressure in the chamber 103 will be automatically adjusted so that it is equal to the pressure within the chamber 94. For example, a preponderance of pressure within the chamber 94 over that existing in the chamber 103 will deflect the diaphragm 102, thereby opening the valve 110 and delivering air under pressure from the source of supply to the chamber 103 and consequently to all of the 45 passages and mechanisms communicating with the delivery passage 106. As the pressure builds up within this chamber, the diaphragm 102 will deflect toward its normal position and will eventually permit the 50 valve 110 to close. If, for any reason, the pressure within the chamber 103 builds up too fast so that it exceeds the pressure in the chamber 94, the diaphragm 102, deflecting in response to the preponderance of pressure within the chamber 103, 55 will open the relief valve 113 and exhaust the excess pressure to the atmosphere. If, during the operation of the apparatus, the steam pressure to which the diaphragm 84

is subjected, increases to such an extent that it moves the plunger 85 and consequently the pilot piston 87 to open the valve 100, the pressure in the upper end of the cylinder 88 will be reduced until it, operating in conjunction with the steam pressure on the diaphragm 84, just counterbalances the pressure of the spring 86, when the diaphragm 84 is in the normal position. This will reduce the pressure within the chamber 94 and consequently occasion a preponderance of pressure within the chamber 103. The diaphragm 102 deflecting in response to this preponderating pressure, will open the relief valve 113 and discharge air from the chamber 103, and its communicating 70 75 passages, until the pressure in the chamber 103 equals the pressure in the chamber 94.

In Fig. 4, I have illustrated an arrangement of apparatus which may be employed, 80 in connection with the apparatus illustrated in Fig. 1, to replace the pressure controlled device 10. That device proportions the pressure of the actuating air delivered to the relay control device 12, in response to variations in the pressure of the steam from 85 the generators controlled, whereas the apparatus shown in Fig. 4 is adapted to admit full actuating air pressure to the device 12, when the steam pressure is normal or above normal, and to fully exhaust that device 90 95 when the steam pressure falls below normal.

In this way the control mechanisms 15 and 16 operate at their full capacity when the steam pressure is below normal and the period, during which they operate at full capacity, is controlled by variations in the steam pressure. It will, of course, be understood that the mechanisms 15 and 16 may be so adjusted that the blower engines and the stoker engine will continue to operate 100 105 while the steam pressure is normal, but at such speed that the steam pressure will merely be maintained but not be built up above normal.

Referring to Fig. 4, the device illustrated 110 includes a casing 116, provided with a cylinder 117, in which a plunger 118 operates, and a cylinder 119, in which a plunger 120 operates. The casing also includes an exhaust chamber 121, which communicates 115 with the atmosphere; a passage 122, adapted to communicate with the air delivery pipe 32 supplying air to the device 12; and a port 123, which communicates with one end of the cylinder 119, and is adapted to receive air under pressure through the pipe 30. The other end of the cylinder 119 communicates with a relief passage 124, which is controlled by a valve 125, controlled in 120 125 its operation by the plunger 118.

The plunger 120 is constructed to operate within the cylinder 119 so that air delivered through the port 123 normally exerts

pressure on both sides of the plunger for the purpose of balancing it. This may be accomplished in any suitable manner and, as illustrated, a restricted port 120' in the plunger is provided for the purpose of insuring the delivery of air to both sides of the plunger. A spring 126 is located between one end of the cylinder 119 and the plunger and is adapted to normally force the plunger to one end of its stroke, in which a valve 127, secured to the plunger, establishes communication between the passage 122 and the atmosphere, or exhaust chamber 121.

The plunger 118 is forced against a diaphragm 128 by means of an adjustable spring 129, which surrounds the stem 130 of the plunger. The opposite side of the diaphragm is exposed to steam pressure delivered through the pipe 21 and this pressure consequently tends to deflect the diaphragm 128 and move the plunger in opposition to the pressure of the spring 129. The stem 130 is so positioned, with relation to the valve 125, that when this takes place it opens the valve and exhausts one end of the cylinder 119 so that the plunger 120 moves, in response to the unbalanced air pressure exerted on it and in opposition to the spring 126, and thereby shifts the valve 127 to such a position that air under full pressure is delivered from the cylinder 119 through the passage 122. It will, of course, be understood that the relief valve 125 is so proportioned that it is capable of discharging more air than can leak around the plunger 120 and that it will, therefore, maintain approximately atmospheric pressure in the end of the cylinder, communicating with the passage 124, when it is opened.

The operation of the apparatus is as follows: When the steam pressure in the passage 11 is below normal or the determined pressure for which the spring 129 is adjusted, the plunger 118 will occupy such a position, with relation to the valve 125, that the valve will remain closed. The plunger 120 will, under such conditions, be subjected on both sides to the pressure of the air entering the port 123 and consequently will be held by the spring 126 in the position shown in the drawing, in which the passage 122 and consequently the pipe 32 is placed in communication with the atmosphere by the valve 127. This, as above described, will permit the plunger 34 of the device 12 to move to the end of its stroke in response to the pressure of the spring 37 and will thereby cause the relay mechanism 14 to deliver full air pressure, through the pipe 17, to the various control mechanisms. When the steam pressure delivered through the pipe 21 returns to normal or to the determined pressure for which the spring 129 is adjusted, the diaphragm 128 will be deflected

by it and will move the plunger 118 so that its stem 130 opens the valve 125. Under such conditions, the plunger 120, moving in response to unbalanced air pressure, will shut off communication between the passage 122 and the atmosphere, and will deliver air under full pressure to the passage 122. This will force the plunger 34 of the device 12 to its extreme position, in opposition to the pressure of the spring 37, and will therefore adjust the relay mechanism to deliver minimum pressure through the pipe 17 to the control mechanisms.

While I have illustrated and described but one embodiment of my invention, it will be apparent to those skilled in the art that various changes, modifications, substitutions and omissions may be made in the apparatus illustrated without departing from the spirit and scope of the invention, as set forth by the appended claims.

What I claim is:

1. In an apparatus of the character described, a source of fluid under pressure, a plurality of controlled mechanisms, a relay mechanism for delivering actuating pressure fluid to said control mechanisms, and a relay control mechanism actuated by variations in the fluid pressure from the apparatus to be controlled for delivering actuating pressure fluid to the relay mechanism, means responsive to the pressure of the fluid delivered to the relay mechanism to increase the pressure of the actuating fluid delivered by said relay mechanism to the control mechanisms in response to a reduction in the fluid pressure from the apparatus to be controlled, and to decrease the pressure of the actuating fluid delivered by said relay mechanism in response to an increase in the fluid pressure from the apparatus to be controlled.

2. A boiler control apparatus comprising a source of fluid under pressure, means responsive to variations in the pressure of steam delivered by the boiler controlled for delivering actuating fluid under pressure from said source of fluid to a relay control device, a relay control device receiving actuating pressure from said means, a relay mechanism controlled by said control device for delivering pressure fluid at an increasing pressure as the steam pressure decreases and for delivering pressure fluid at a decreasing pressure as the steam pressure increases, and means responsive to the pressure delivered by said relay for controlling the operating of said boiler.

3. In combination in a boiler control apparatus, a fluid pressure actuated control mechanism for controlling the operation of a boiler accessory, a relay mechanism for delivering actuating pressure to said mechanism, means controlled by variations in

- the steam pressure of the boiler controlled for controlling the operation of the relay, and means responsive to variations in speed of the accessory for counterbalancing the 5 actuating pressure.
4. In combination in a boiler control apparatus, a fluid pressure actuated control mechanism for controlling the operation of a boiler accessory, a relay mechanism for 10 delivering actuating pressure to said mechanism when the steam pressure of the boiler controlled decreases, means controlled by variations in the steam pressure for actuating said relay, and means responsive to a 15 variation in speed of the accessory for counterbalancing the actuating pressure.
5. In a stoker control apparatus, a control mechanism for controlling the operation of an engine driving a blower supplying air to 20 the stoker controlled, comprising a valve for delivering steam to the blower engine, a pressure actuated plunger for opening the valve, means subjected to the pressure of the fluid pumped by the blower controlled for 25 opposing the movements of the plunger and for closing the valve, and means responsive to variations in the pressure of the steam generated for controlling the delivery of pressure to the plunger of said control 30 mechanism.
6. In combination with a boiler to be controlled, a furnace, a blower for delivering forced draft to the furnace, an engine driving said blower, and means responsive to 35 variations in the pressure of steam delivered by said boiler and to the pressure generated by the blower for controlling the operation of said engine.
7. In combination in a boiler control apparatus, a blower for delivering air to the furnace operating in conjunction with the boiler controlled, and means responsive to the pressure of the steam generated by the boiler controlled and reacted upon by the 45 pressure generated by the blower for controlling the operation of the blower.
8. In combination with a boiler to be con- trolled, a furnace, a device for controlling the draft delivered to the furnace, and means responsive to variations in the pressure of the steam generated by the boiler and to variations in the pressure of the draft for controlling the operation of the draft controlling device.
9. In combination with a boiler and its co- 55 operating stoker, a stoker control apparatus, comprising a blower for delivering forced draft to the stoker, an engine for driving the blower, an engine for driving the stoker, means responsive to variations in the pressure of the steam generated and reacted upon by the pressure developed by the blower for controlling the operation of the driving engine of the blower, and means for 60 controlling the operation of the stoker engine in response to variations in the steam pressure generated by the boiler.
10. In combination with a boiler and its stoker, a centrifugal governor for controlling the operation of the stoker, means for 70 varying the effectiveness of the governor for controlling the operation of the governor to cause it to operate at maximum capacity when the boiler pressure falls below a determined pressure, and means responsive to the 75 boiler pressure for controlling the operation of the first mentioned means.
11. In combination with a boiler, and its stoker, a blower for delivering forced draft to the stoker, a control mechanism for the 80 stoker, fluid delivery means responsive to variations in pressure of the steam delivered by the boiler controlled, means responsive to the pressure of the fluid delivered by said first mentioned means and adapted to deliver actuating fluid pressure to the control mechanism and for increasing the actuating pressure delivered as the steam pressure decreases, and decreasing the actuating pressure as the steam pressure increases.
- In testimony whereof, I have hereunto subscribed my name this 30th day of October, 1915.

HERBERT T. HERR.
